UNITED STATES PATENT OFFICE

172,943

RECEPTACLE FOR A COMPACT AND LIPSTICK CASE

Sam Aprile, Woodside, N. Y.

Application April 7, 1954, Serial No. 29,889

Term of patent 14 years

(Cl. D86—10)

To all whom it may concern:

Be it known that I, Sam Aprile, a citizen of the United States of America, residing in Woodside, county of Queens, and State of New York, have invented a new, original, and ornamental Design for a Receptacle for a Compact and Lipstick Case, of which the following is a specification, reference being had to the accompanying drawing, forming part thereof, wherein,

The stippled portions on the drawing represent contrasting areas.

I claim:

The ornamental design for a receptacle for a compact and lipstick case, substantially as shown and described.
